UNITED STATES PATENT OFFICE.

ENOCH PROUTY, OF CHICAGO, ILLINOIS.

SILL FOR SKELETON CAR-FRAMES.

No. 832,623.

Specification of Letters Patent.

Patented Oct. 9, 1906.

Application filed January 8, 1906. Serial No. 295,062.

To all whom it may concern:

Be it known that I, ENOCH PROUTY, a citizen of the United States, residing at Chicago, in the county of Cook and State of Illinois, have invented new and useful Improvements 5 in Sills for Skeleton Car-Frames, of which the following is a full, clear, concise, and exact description, reference being had to the accompanying drawings, forming a part of this specification.

My invention relates to railway-cars, and particularly to the manner of constructing the frame of the same.

One of the objects of my invention is to 15 provide a sill for a car-frame which shall have maximum strength with minimum amount of material and which shall be so constructed that the same may be readily accessible on all sides for the purpose of connecting the other parts of the car thereto.

I have illustrated my invention in the accompanying drawings, in which—

Figure 1 is a partial side view of the car, showing a position that my sill assumes in 25 the car. Fig. 2 is an enlarged detail cross-section of a portion of a bottom, taken on line 4-4 of Fig. 4, showing the manner of constructing my sill and the manner of bracing the same. Fig. 3 is a detail perspective view 30 of my sill and other structural parts of the car. Fig. 4 shows a modification of my sill construction. Fig. 5 shows another modification of my sill construction; and Fig. 6 is a partial plan view of my car, showing the 35 skeleton construction of the bottom thereof.

In the preferred embodiment of my invention the sills of my car are constructed of 40 pressed-steel U-shaped members. These members are preferably formed from two L-shaped members 1 and 2, having adjacent sides 3 and 4 overlapping and suitably secured together, as illustrated in Fig. 2. The L-shaped member which forms the outside of the sill preferably has the side portions 45 thereof of greater length than the other side portion, whereby an upwardly-extending flange 5 is formed. The side 4 of the L-shaped member 1 is also of greater length than the side 3, whereby a flange 6 is formed 50 on the bottom of the sill. At intervals along the top of the sill the two sides are braced and connected together by means of a T-shaped brace 7, having a downwardly-extending flange 10, preferably formed from

cast-steel. The head 8 of this block is secured to the inside of the outer vertical side portion by rivets or other means and has a portion 9 thereof extending up beyond the upper edge of the side of the sill. The downwardly-extending flange 10, formed upon the 55 stem 11 of the T-shaped tie-block, is attached to the outside of the inner vertical side portion of the sill by suitable rivets or other securing means.

The two side sills of the car are constructed in the manner above described and at suitable intervals are connected together by means of a bottom tie 12, which extends between the same and is fastened by suitable rivets to the flanges 6 of the sills. As an additional means of supporting and connecting the side sills a truss 13 is arranged between the two side sills immediately in front of each of the bottom ties 12, and this truss is preferably of the construction shown in Fig. 2, 60 having a horizontal portion 14 riveted or otherwise secured to the under side of the stem 11 of the T-block 7. The truss extends downwardly beneath the center sills 15 and 16 of the car and has riveted thereto flat supports 17 and 18, which extend longitudinally of the car and aid in carrying and bracing the center sills 15 and 16, to which the bottoms of these sills are attached. These 65 center sills are preferably constructed of T-beams, as shown in Fig. 1. Between the side sills and on top of the same horizontal members 19 of the truss 13, which also constitute floor-ties, are laid at suitable intervals, and these ties are riveted at their central point to the tops of the center sills 15 and 16 and at their ends to the tops of the 70 stems 11.

The ends of the cars are constructed of car end sills 20 of substantially the same construction as the side sills and secured thereto by means of the angle-pieces 21. These end sills extend inwardly toward the center of the car to the center sills 15 and 16, to which they are also secured. The platform side 75 sills 22 of the car are also constructed in substantially the same manner as are the side sills of the car and are secured to the end sills by suitable angle-pieces 23 at one end and to the platform end sills 24 at their other end. 80 The platform end sills are also of the same general construction as the side sills of the car. It will be noted that the center sills 16

and 17 of the car extend the entire length thereof, including the length of the platform.

The sides of the car may be constructed in any suitable manner; but as my peculiar construction of sill makes one manner of constructing the sides of the car particularly advantageous I prefer to construct the same in this manner. At regular intervals vertical posts 25 are secured between the two vertical members of the sills by means of rivets or bolts. These vertical posts provide means to which the sides of the car may be rigidly attached. In one form, which is particularly advantageous in constructing passenger-cars, I provide longitudinally-extending wooden rails or strips 26, which are bolted to vertical posts 25, and wooden strips 27, which are bolted at the bottom of the side sills. The veneer 28 of the sides of the car is attached 20 to these strips in any suitable manner. This is only one manner of constructing the sides of the car, and any other manner may be used, depending upon the use to which the car is to be placed. For instance, if desired 25 to construct an all-steel car having an outer veneer of wood, the steel sheeting may be secured directly to the vertical posts and side sills and the wood veneer secured thereto. Also the bottom lining of the car may be 30 formed of steel sheeting as well as the inner sides. If desired, a floor and side veneer may be placed over the steel lining. In freight-cars the sides may be sided up with wood or steel sheeting, depending upon the 35 manner in which the car is intended to be used.

While I have described one form of my invention, it will be understood that I do not wish to limit myself to the specific details 40 thereof and that the U-shaped sills may be formed in any other manner, if so desired.

I have described my sill as being formed of pressed steel, this being the usual form of steel used in its construction and having 45 been found the most advantageous. It will be understood that my sills may be formed from members made in any desired manner— as, for instance, by rolling, forging, &c.

Having thus described my invention, what I claim as new, and desire to secure by Letters Patent, is—

1. A sill for skeleton car-frames comprising a steel substantially U-shaped member formed of two substantially L-shaped members having adjacent sides overlapping and 55 suitably tied together, one of the vertical sides of said member being longer than the opposite vertical side of said member.

2. A sill for skeleton car-frames, comprising a steel substantially U-shaped member 60 formed of two substantially L-shaped members, having adjacent sides overlapping and suitably tied together, one of said sides being longer than the opposite side, whereby a projecting flange is formed.

3. A sill for skeleton car-frames, comprising a substantially U-shaped steel member formed of two substantially L-shaped members having adjacent sides overlapping and 70 suitably tied together, one of the vertical sides of said member being longer than the opposite vertical side, and one of the horizontal sides of said member being longer than the opposite horizontal side.

4. A sill comprising a steel substantially 75 U-shaped member formed of two substantially L-shaped members having adjacent sides overlapping, one of the vertical sides of said member being longer than the opposite vertical side, and one of the horizontal sides 80 being longer than the opposite horizontal side, and a T-shaped tie-block for tying and bracing the disconnected ends of said U-shaped member, the head of said T-shaped tie-block being secured to one of said L- 85 shaped members, and the stem of said T-shaped tie-block having a flange arranged to be secured to the other of said members.

In witness whereof I have hereunto subscribed my name in the presence of two witnesses.

ENOCH PROUTY.
